UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

TEXTILE-MACHINE.

1,175,710.

Specification of Letters Patent. Patented Mar. 14, 1916.

Application filed May 20, 1911. Serial No. 628,474.

To all whom it may concern:

Be it known that I, HOWARD D. COLMAN, a citizen of the United States, residing at Rockford, in the county of Winnebago and State of Illinois, have invented certain new and useful Improvements in Textile-Machines, of which the following is a specification.

In the operation of spinning textile fibers into yarn, the yarn is wound upon bobbins or the like, each bobbin containing a single thread. To produce a warp, the common practice is to rewind the yarn from the bobbins onto spools or cheese-tubes, each 15 spool or tube containing a single thread of a length equivalent to the amount of yarn upon a plurality of bobbins, the threads upon the successively unwound bobbins being tied end to end by the operatives. The 20 yarn upon a sufficient number of spools or cheeses is then rewound upon a section beam. It has also been proposed to rewind yarn upon a section beam directly from the bobbins, the bobbin threads being tied end to 25 end by the operatives.

The primary object of this invention is to provide a winder having means for automatically uniting the ends of the threads on bobbins to the ends of the threads on the 30 spools, cheeses, section beam or other yarn masses produced by the winder.

Among the secondary objects of the invention are to provide means for finding the end of the thread upon a yarn mass; means 35 for bringing together at a knotter or other thread-joiner the end of the thread of a reserve bobbin and the end of the thread of another yarn mass; means for taking up slack in the united threads; means for keeping 40 the united threads in a certain relation to said other yarn mass; means for placing the yarn mass in operative relation to the winding means; and means for gaging yarn masses.

The invention will be herein disclosed as embodied in a machine for rewinding the 45 yarn from bobbins to form cheeses, but it will be understood that the invention is not limited to the production of such yarn masses, and that various features of the invention are applicable to other classes of textile machines.

In the accompanying drawings, Figure 1 is a top plan view of one end portion of a

winder embodying the features of my invention. Fig. 2 is a similar view of the opposite end portion of the winder. Fig. 3 is a side elevation of the portion shown in Fig. 2. Fig. 4 is a transverse sectional view through the machine. Fig. 5 is a fragmental 55 side elevation of one of the "units" of the winder. Fig. 6 is a fragmental front elevation, and Fig. 7 a fragmental top plan view of said unit. Fig. 8 is a fragmental side elevation of the unit, representing the thread 60 as exhausted, and the unit about to be thrown out of operation. Fig. 9 illustrates the unit as thrown out. Fig. 9^a is a fragmental elevation showing certain parts in the position illustrated in Fig. 8. Fig. 9^b 65 is a plan view of some of the parts represented in Fig. 9^a. Fig. 10 is a horizontal sectional view on the same scale as Fig. 7, and showing the detector mechanism in the position indicated in Fig. 8. Fig. 11 illustrates the detector mechanism as being 70 placed in position to receive the new thread that is to take the place of the exhausted thread. Fig. 12 represents the detector 75 mechanism as being in readiness to receive the new thread. Fig. 13 is a longitudinal central section through one of the tubes on which the thread-masses or "cheeses" are formed, showing also the support for the tube. Fig. 14 is an end elevation of the tube 80 and its support. Fig. 15 is a section on line 15 15 of Fig. 13. Fig. 16 is a section on line 16 16 of Fig. 14. Fig. 17 is a front elevation of a winder-tending machine arranged to travel around the winder for the 85 purpose of tying reserve threads to exhausted threads and placing the thrown out units in operation. Fig. 17^a is a fragmental front elevation illustrating an electric switch. Fig. 18 is a fragmental view of the advancing 90 side of said traveling mechanism, showing it in operative relation to the winder. Fig. 18^a is a detail of an automatic stop mechanism for said traveling mechanism. Fig. 19 illustrates the action of a feeler or gage 95 100 for detecting full-size cheeses. Fig. 20 is a fragmental horizontal sectional view through the traveling mechanism. Figs. 21 and 22 are fragmental vertical longitudinal sections through said mechanism. Fig. 21^a 105 is a fragmental vertical sectional view illustrating an electric switch. Fig. 23 is a transverse vertical sectional view illustrating

ing the means for causing said mechanism to travel and for transmitting power thereto. Fig. 24 is a similar view showing a portion of the means for supporting and guiding the traveling mechanism. Fig. 25 is a fragmental vertical sectional view illustrating with other mechanisms, the means for finding the end of the exhausted thread on the cheese. Fig. 26 is a fragmental horizontal section, representing the traveling mechanism as having moved along from the position shown in Fig. 25 and illustrating a means for severing an exhausted thread that has become wrapped around the tube 15 beside the cheese, as indicated in Fig. 25. Fig. 27 is a fragmental horizontal section showing the winder-tending mechanism as having traveled a slight distance beyond the position illustrated in Fig. 26. Fig. 28 is a section on line 28 28 of Fig. 27. Fig. 29 is a section on line 29 29 of Fig. 28. Fig. 30 is a fragmental sectional view through the severing means above referred to taken in the plane of line 30 in Fig. 36. Fig. 31 is a fragmental vertical section showing the winder-tending mechanism as being in the same position as shown in Fig. 27. Fig. 32 is a fragmental transverse vertical section illustrating parts shown in Figs. 25 to 31. 30 Fig. 33 is a view similar to Fig. 32 representing a bight of the exhausted thread as drawn down into position for one strand to be moved into the knotter. Fig. 34 also is a fragmental transverse section, showing 35 said strand as having been placed in the knotter. Fig. 35 is a fragmental perspective view of the arm that draws down the bight of thread, and the arm that moves a strand of the bight into the knot-tying 40 mechanism. Fig. 36 is a fragmental horizontal section showing the knotter and adjacent mechanisms. Fig. 37 illustrates in plan view a clamp associated with the knotter. Fig. 38 is a sectional view taken 45 in the plane of dotted line 38 in Fig. 36. Figs. 39 and 40 are side and plan views, respectively, of a cam for actuating the arm that moves the thread into the knotter and a shear for severing said thread. Fig. 41 is a 50 fragmental horizontal section showing, among other things, the shear just mentioned, an exhaust air tube comprised in the end-finding mechanism, and the arm that draws down a bight of the found thread. 55 Fig. 42 is a side elevation of parts shown in Fig. 41. Fig. 43 is a rear side view illustrating certain cam bars fixed in the framework of the traveling mechanism. Figs. 44 and 45 show a means for stopping rotation 60 of the cheese. Fig. 46 is a top plan view of the parts mounted on the top of the carriage of the traveling mechanism. Fig. 47 illustrates a means for swinging the arm that draws the exhausted thread to the knotter. Figs. 48, 49 and 50 represent a portion of a

means for preventing the new thread from being pulled along by the mechanism, or, in other words, to keep the new thread in substantially the vertical plane of the unit. One of the thread shears also is shown in Fig. 49, and is further illustrated in section in Fig. 51. Fig. 52 is a fragmental elevation looking in the direction opposite to that in which Fig. 18 is viewed, and showing the plate 239 as about to pass out from under the cheese. Fig. 53 is a fragmental view illustrating the relation of the path of movement of the knotter to the winder unit. The knotter is to be understood as traveling toward the observer.

The embodiment which I have selected to illustrate the invention consists of a machine for winding yarn from a bobbin *a* or *b* onto tubes *c* to form "cheeses" *d*, and a winder-tending mechanism arranged to travel along the winder and attach the ends of the yarn on bobbins to the ends of the yarn on the cheeses. The winder consists of an elongated framework 1 providing two parallel "sides," each side being equipped with means for rotatably supporting bobbins and means for supporting and rotating cheese tubes or cheeses. The length of the sides and the speed of winding are so proportioned to the quantity of yarn usually wound upon bobbins and to the speed at which the winder-tending mechanism travels that shortly before said winder-tending mechanism reaches a given bobbin, said bobbin will have been emptied or "exhausted." It will, therefore, be understood that the winder-tending mechanism ties the end of the yarn on a fresh bobbin to every cheese, as the winder-tending mechanism progresses around the winder.

The cheeses are rotated through peripheral contact with rolls or drums 2, each drum having a peripheral cam groove 3 in which the yarn runs to the cheese. In the rotation of the cam drum, the groove 3 guides the yarn back and forth and thus builds up the cheese. The cam drums 2 are fixed upon two shafts 4 (Fig. 4) extending longitudinally of the supporting frame. These shafts may be driven in any suitable manner, as for example, by means of belts (not shown) extending from any preferred source of power and running over pulleys 5 (Fig. 1) fixed on the shafts.

Fixed to the supporting frame adjacent to each cam drum is a bracket 6 having a bearing 7 at its upper end. A cheese-supporting lever 8 is provided upon one side and near one end with a pivot 9 (Figs. 9^a and 9^b) which is mounted in the bearing 7, said pivot being rigid with the lever. At the end of the long arm of the lever 8 is means for rotatably supporting a cheese, the means employed for this purpose in the present embodiment being illustrated in Figs. 130

13 to 16. Upon a spindle 10 fixed to the lever 8 is rotatably mounted a sleeve 11 provided with a bearing bushing 12. A headed screw 13 retains the sleeve 11 upon the 5 spindle 10. At the outer end of the sleeve 11 are two disks 14 and 15 secured together and to the sleeve 11 by screws 16 and pins 17. The tube *c* is carried by the sleeve 11 and disks 14 and 15, and is held against 10 endwise movement in one direction by a flange 18 on the sleeve 11. Longitudinal displacement in the opposite direction is prevented by a spring-pressed detent 19 located in a recess formed between the disks 15 15 14 and 15, the operating end of said detent being arranged to enter an annular groove 20 in the tube *c*. The detent may be withdrawn by depressing a button 21 mounted in a recess in the disk 15, the stem 22 of 20 said button having a conical portion arranged to act upon the wall of an opening 23 formed in the detent 19. The spring 24 for the detent also serves to restore the button 21 to its normal position, the restoring 25 movement of the button being limited by a head 25 on the stem 22.

The sleeve 11 is chambered as at 26 to contain a lubricant, the chamber communicating with the surfaces to be lubricated 30 by means of ducts or ports 27. The filling opening 28 is provided with a screw closure 29.

To the short arm 8^a of the lever 8 is pivoted a depending link 30 (Fig. 5) which 35 may be made in the form of an elongated loop, as shown in Fig. 6. When the yarn exhausts, devices to be presently described, swing the link 30 from its normal vertical position to a position within reach of a continuously oscillating hook 31 (Fig. 5) which 40 pulls the link downward and thus throws the lever 8 from the position illustrated in Fig. 8 to that shown in Fig. 9, whereby the cheese is withdrawn from the cam drum 45 and the rotation of the cheese suspended. The hooks 31 are fixed upon the shafts 32 which may be rocked by any suitable means. That represented in Fig. 4 comprises a wheel 33 carrying a crank pin which is connected by pitmen 34 to crank arms 35 fixed 50 on the shafts 32. The wheel 33 is driven from one of the shafts 4 through a gear train 36.

A bell-crank lever 37 (Figs. 8 and 9^a) is 55 pivoted at 38 in the bracket 6. The arm 37^a of said lever is acted upon by a tension spring 39, while the arm 37^b normally bears against a lug 40 cast integral with or otherwise suitably secured to the pivot 9 of the 60 cheese-supporting lever 8. When the formation of a cheese is started, the lug 40 stands at an acute angle to the arm 37^b, and the spring 39 is able to exert sufficient pressure to insure proper driving contact between the tube and the cam drum. As the 65

diameter of the cheese increases, the lug 40 turns toward a position at a right angle with the arm 37^b, whereby the spring pressure transmitted to the lever 8 decreases. This graduation in pressure is provided so 70 that the central portion of the cheese shall be harder than the outer portion, thus lessening the spreading tendency exerted by the outer layers of yarn on the inner layers. The friction of the arm 37^b against the lug 75 40 also tends to prevent the cheese from bounding and to keep it running in a true circle.

When the cheese is thrown out of driving contact with the cam drum 2, a lug 41 fast 80 on the pivot 9 strikes against the arm 37^b, whereby said arm serves to yieldingly arrest the movement of the lever 8 and to determine the thrown-out position of the cheese.

If desired, guard plates 42 may be provided between the cheeses, the ends of said plates serving to prevent the loose end of an exhausted thread from being thrown sideways by the cam groove 3 beyond the side of the cheese, so that such loose end shall lie 90 upon the periphery of the cheese.

The bobbins are supported in bobbin-holders 43 and 44 (Fig. 4) which are arranged in pairs, the pairs of bobbin-holders being fixed upon rods 45 extending longitudinally of the machine frame. If desired, the rods 45 may be supported for adjustment, as by means of slotted arms 46 and bolts 47. The two bobbin-holders of each pair support a bobbin being unwound and a 100 reserve bobbin. The end of the yarn on the reserve bobbin is held in a clamp carried by an arm 48 which is fixed to the machine frame. Said clamp comprises a stationary jaw 49 (Figs. 5 and 7) and a spring jaw 50 fixed at 51 to the arm 48. The outer ends of the clamping jaws are formed to provide a flaring mouth to facilitate the manual insertion of the thread end. Lugs 52 on the jaw 50 constitute stops to limit the 105 extent to which the thread-end may be inserted in the clamp. In order that the portion of the thread-end to be operated on by the winder-tending mechanism shall always occupy a definite position regardless of 110 which bobbin-holder contains the reserve bobbin, and regardless of the position from which the thread leaves its bobbin, a bridge 115 53 is provided on the arm 48 at a suitable distance below the clamp 49 50, across which bridge the thread lies in extending from the reserve bobbin to the clamp.

In passing from the active bobbin to the cam drum, the running thread extends into operative relation to a detector means, which means may be of any suitable character. That shown in Figs. 5 and 6 comprises the following devices: An arm 54 extending downwardly from the arm 48 has fixed thereto two horizontally extending wires 55 120

56. The wire 55 is straight, save for a bend forming a notch or recess 57 to receive the active thread. The wire 56 has a similar alined bend 58 therein. A portion of the 5 wire 56 is bent to provide the guide portion 59 and the guard portion 60. Coöoperating with the guide 59 is a guideplate 59^a supported by the arm 48. A vertical rock shaft 61 is supported in bearings 62 and has fixed 10 to its lower portion a horizontally extending finger 63 adapted to pass between the wires or fingers 55 56. The finger 63 has a notch 64 therein as shown in Fig. 10, the active thread passing through the notches 57 58 15 as indicated in Figs. 5, 6 and 7. The finger 63 is pressed against the active thread through the medium of a torsion spring 65. When the active thread exhausts, through the emptying of the bobbin or the breakage 20 of the thread, the latter can no longer restrain the finger 63 against the torsion of the spring 65, whereupon the finger 63 is swung into the position represented in Figs. 8 and 10, during which swinging movement 25 a pin 66 on the shaft 61 swings the link 30 into reach of the hook 31. Said hook upon its next downward movement catches the link 31 and throws the cheese into the position shown in Fig. 9, where it remains until 30 the winder-tending mechanism arrives and ties in the reserve thread.

Should the link 30 be swung toward the hook 31 while said hook is moving downwardly and is past the point where it can 35 catch said link, the latter stops against the edge 31^a of the hook until the hook has completed its downward movement and has risen clear of the link, whereupon the link 30 (still under the influence of the spring 40 65) completes its rearward movement and is caught by the hook upon its next downward movement.

67 is a guide fixed in the machine frame for preventing casual lateral displacement 45 of the link 30. 68 is a pin fixed in said guide for limiting outward swinging movement of the link.

When the hook 31 rises after pulling down the link 30, said link fulcrums on a projection 50 69 (Fig. 9); and as the rising of the hook 31 allows the cheese to descend toward the position shown in said figure, the link is drawn up by the cheese, across said projection, and thereby swung so that its lower 55 end is out of the range of the hook, whereby the hook is prevented from engaging the link after the cheese is thrown out.

Each drum 2, arm 8, and pair of bobbin 60 holders, with their appurtenant devices, will be hereinafter termed a winder.

The traveling winder-tending mechanism is shown in front elevation in Fig. 17, with portions omitted. It is supported for movement in an endless circuit about the winder by means of two rails 70 71 fixed in the

winder framework. On the framework 72 of the winder-tending mechanism, are two rollers 73 (Figs. 17, 23 and 24) that run upon the upper edge of the rail 70, two rollers 74 that bear upon the inner face of the rail 70, and a roller 75 (Figs. 17 and 18) turning on a vertical axis and running along the rail 71. The winder-tending mechanism is actuated and caused to travel by power derived from a suitable source, such as an 75 electric motor 76 mounted upon the framework 72, current being supplied to the motor by any preferred means. On the armature shaft is fixed a bevel pinion 77 (Fig. 23) meshing with a bevel gear wheel 78 80 fixed on a shaft 79 mounted in a bearing 80. On the lower end of the shaft 79 is a pinion 81 meshing with a spur gear 82. Fixed with relation to the gear 82 is a pinion 83 that meshes with a spur gear 84. The 85 last mentioned gear is connected through a clutch 85 with the main shaft 86. On this shaft is a pinion 87 meshing with rack teeth 88 formed on the rail 70, said pinion being herein shown as connected with the shaft 90 86 by means of a hand-operable clutch 89. An idler pinion 90 mounted in the framework 72 meshes with the rack 88. Below said idler pinion is a roller 91 bearing against the lower edge of the rail 70. A 95 shaft 92 is driven from the shaft 86 through the medium of spiral gearing 93 (Fig. 20.) When it is desired to actuate and feed the winder-tending mechanism by hand, a crank 100 may be applied to the squared end of a shaft 94 (Fig. 18) connected to the shaft 86 by means of bevel gearing 95.

Exhaust air currents are utilized in finding and picking up the loose thread-end on the cheese, in holding the threads, and in carrying away the pieces of thread sheared from the exhausted and reserve threads in the uniting operation. These currents may be produced by any suitable means, as, for example, an exhauster 96 (Figs. 17 and 46) 110 mounted on the framework 72, the shaft 97 of the exhauster being coupled to the shaft of the motor 76. To separate the clippings from the air current I provide a centrifugal separator 98 secured to the framework 72 115 and connected to the exhauster by means of a tube 99. The air current enters the separator through a tube 100 which has two branches 101 102 extending to the end-finder and the knoter, respectively. 120

The mouth 103 (Fig. 27) of the tube 101 is formed between fixed plates 104, 105, 106, 107. In the upper edge of the plate 105 is a notch 108 (Fig. 32) having a restricted throatway or entrance.

Fixed in the framework of the winder-tending mechanism and extending longitudinally thereof is a cam bar 109 (Figs. 18, 20, 21 and 43) having inclined surfaces 110 111 and dwells 112 113. As the winder-tending 130

mechanism advances, the cam 110 passes beneath the arm 37^a of a given unit and raises said arm, thus rocking the arm 37^b away from the projection 41.

5 The framework of the winder-tending mechanism comprises two rearwardly projecting brackets 114 (Figs. 18 and 21) to which is fixed a plate 115 having an inclined cam surface 116 and a dwell 117. A moment 10 after the cam 110 has engaged the arm 37^a the cam 116 engages the end 8^a of the lever 8 and tilts said lever to lift the cheese above the horizontal plane of the end-finder roll 118 (Fig. 22). When the dwell 117 has 15 passed off the lever, the cheese drops onto the roll 118. The latter is fixed upon a shaft 119 which is connected by gears 120 to a shaft 121 (Fig. 20) which is driven from the shaft 92 through the medium of gears 20 122 123 124 (Fig. 18). The end-finder roll 118 is located with one end adjacent to the mouth 103 (Fig. 26) of the suction tube 101, said mouth being slightly below the top of the roll. Said roll rotates in the direction to unwind the yarn. As the roll 118 passes out from beneath the rotating cheese, the exhaust current picks up the loose thread-end and carries it into the tube 101. At the side of the mouth 103 opposite 25 to the roll 118 is a roll 125, the distance between said rolls being less than the width of the cheese, so that before the roll 118 passes completely out from under the cheese, the roll 125 is in position to support it. The 30 roll 125 is fixed upon a shaft 126 (Fig. 22) which is driven from a shaft 127 (Fig. 44) through gears 128, the shaft 127 being driven from the shaft 119 through a train of three gears 129, (Figs. 18 and 20). 35

40 As the traveling mechanism passes along beneath the cheese, the found end extends from the mouth 103, through the notch 108 to the cheese, generally to the region of contact of the cheese and the roll 125, as shown in Figs. 27 and 32. The thread portion 45 thus extending between the notch 108 and the cheese is caught in the notch 130 of a swinging arm 131, and a bight thereof is drawn down by said arm to the knot-tying mechanism, the downward movement of the 50 arm 131 carrying one of the strands into a hook 131^a as shown in Figs. 33 and 41, which hook is located adjacent to the tube 101. The roll 125 is continuously rotated to 55 rotate the cheese in the direction to unwind yarn, whereby slack is provided for the arm 131, some thread also being drawn from the tube 101. As shown in Figs. 25 and 35, the notched head of the arm 131 is thicker than 60 said arm, in order to space the strand leading to the air tube away from said arm, for a purpose to appear later herein.

132 is a guard plate and 133 a guard wire to prevent the drawn-down thread from 65 catching in the mechanism as the mecha-

nism advances. Portions of said guard plate and guard wire extend substantially parallel and thus form between them a guideway for the thread. See the plan views, Figs. 20 and 49, and the elevation, 70 Fig. 33. The chief function of the wire 133 is to hold the thread in the path of a hook 210 hereinafter described.

The arm 131 is fixed upon a rock shaft 134 (Figs. 22 and 47) which is oscillated by 75 means of a pinion 135, a lever 136 having a gear sector 137 at one end meshing with said pinion, and a roller stud at its other end running in the groove of a cam disk 138 on the shaft 92. 80

Sometimes when a thread exhausts, it escapes from between the guard plates 42 and is wound on the tube beside the cheese, as indicated in Fig. 25. As the mouth 103 passes below the rotating cheese, the exhausted thread is found and a bight thereof drawn into the tube 101. In order to prevent any more thread from being wound on the tube and to obtain a free end, I provide a shearing mechanism comprising the 90 following described parts: A shear blade 139 (Figs. 26 to 30) is rigidly secured to a slide 140 and is spaced above said slide by a block 141. Said slide is guided in ways 95 142 and by the portion 106^a of the plate 106, and is reciprocated across the mouth 103 by means of a lever 143 and a cam disk 144 (Fig. 32), said cam disk being mounted upon a shaft 145. A shear blade 146 and a finger 147 (Fig. 28), are secured upon the 100 upper end of a shaft 148 in substantially parallel relation and spaced apart, the space between said blade and finger being sufficient to enable them to pass at opposite sides of (above and below) the shear blade 139. 105 The shaft 148 is rocked by means of a crank arm 149 (Fig. 22) engaging a cam 150 on the shaft 145. Shaft 145 is driven by a chain, belt 151 (Fig. 18) running over sprocket wheels 152 153 fixed on the shafts 110 92 and 145, respectively, and over a slack-take-up roller 154.

When the travel of the winder-tending mechanism has brought the parts into about the position shown in Fig. 25, the shear blade 139 is advanced to intercept the thread, should the latter be wound on the tube, the shear blade 146 also moving from the position indicated in dotted lines in Fig. 27 to that shown in Fig. 31, to shear 115 such thread between the blades 139 146. The finger 147 prevents the blade 146 from pressing against and cutting the portion of the thread extending between the notch 108 and the cheese, and also serves to insure that said portion shall occupy a predetermined position with reference to the arm 131, whether said portion extends from between the cheese and the roller 125 as shown 120 125 in full lines in Fig. 31 or from some other 130

point upon the periphery of the cheese, as indicated in dotted lines in said figure.

If a strong current be used in the suction tube 101, it may be desirable to provide means to prevent the air current from destroying the thread by untwisting the latter and carrying away its component fibers. Such means may comprise a screen 155 (Fig. 41) arranged to be swung into and out of position to obstruct the passage of the thread through the tube. Contact of the thread with the screen prevents the thread from untwisting. Said screen is fixed to a pivot 156, to which is rigidly attached an arm 157 which is connected by a link 158 to one end of a lever 159, the other arm of the lever carrying a roll that lies in the groove of a cam 160. The cam is fixed on the shaft 92.

As hereinbefore stated, the found end is carried by the arm 131 to the thread-uniting mechanism. While this mechanism may be of any suitable character, I have herein shown a means for tying knots, the mechanism being substantially similar to that fully described in Patent No. 959,592, dated May 31, 1910. Briefly described, the knotter comprises a tying bill 161 (Fig. 38) and a stripper disk or hook 162, said bill and hook being rotated by means of gearing actuated by a shaft 163 (Fig. 36). Said shaft carries a pinion 164 meshing with a gear 165 fixed on a shaft 166 (Figs. 20 and 34). On the shaft 166 is fixed the star wheel 167 of a Geneva stop motion, said stop motion further comprising a pin disk 168 mounted on the shaft 86.

As indicated in Fig. 38, the knotter is located directly below the inlet end of the suction tube 102. The upper wall of said tube has a thread-receiving notch 169 therein, as indicated in the plan view, Fig. 36, said notch being vertically alined with the tying bill when the latter is in its initial or thread-receiving position. (See Fig. 53.) Said notch is continued through a block 170 (Fig. 38) fixed in the tube 102. The lower wall of the tube is similarly notched, as shown at 171. A bracket 172 is fixed to the lower side of the knotter framework (Figs. 34, 38 and 53) and has a notch 173 therein alined with the notches 169 and 171. Fixed to the lower side of the bracket 172 is a plate 174, a portion of said plate being spaced away from the bracket.

It will be remembered that the reserve thread is held in the clamp 49 50 (Figs. 5 and 7), the portion of the thread extending between the clamp and the bridge 53 being in the path of the approaching tying-bill 161 and thread guides 169, 171 and 173, as shown in Fig. 53. About the time the tying-bill and thread-guides reach the reserve thread, the clamp 49 50 is opened by reason of the outer end of the spring

jaw 50 being engaged and pressed aside slightly by a finger 175 (Figs. 36, 38 and 53) mounted adjacent to the suction tube 102. Means to open the clamp 49 50 may, however, be dispensed with, as the thread 70 may readily be pulled therefrom. Just before the reserve thread is released it is clamped in the notch 169 by a member 176 (Figs. 36 and 53) pivoted at 177 and actuated by a cam 178, arm 179 and spring 180, 75 said cam being fixed on the shaft 86.

A clamping member 181 (Fig. 37) pivoted at 182 and operated by a cam 183, an arm 184, and a spring 185 is adapted to clamp between itself and the lower side of 80 the suction tube the threads extending through the notch 171.

When the arm 131 has pulled a bight of the exhausted thread into the position represented in Fig. 33, the strand leading 85 to the air tube 101 is carried into the tying-bill 161 and the guide-notches 169, 171 and 173 by a swinging arm 186 (Fig. 36). The arm 186 is provided with two notched thread-engaging plates 191, 192 (Fig. 35), 90 the latter having a prolonged and somewhat hooked finger 192^a into which the strand leading to the air tube 101 is carried by the downward movement of the arm 131. The finger 192^a is enabled to receive said strand 95 by reason of the latter being spaced away from the arm 131, due to the greater thickness of the head of the arm.

The arm 186 is fixed to the lower end of a vertical shaft 187. To the upper end of 100 said shaft is fixed an arm 188 (Figs. 39 and 40) carrying a roll running in the groove 189 of a cam disk 190, said disk being mounted on the shaft 86. The form of the cam groove 189 is such that the arm 186 is 105 first advanced to position the finger 192^a in the path of the strand leading to the air tube 101; after the arm 131 has descended and laid said strand across the finger 192^a, the arm 186 is advanced still farther to carry 110 said strand onto the tying-bill 161 and into the guide-notches 169, 171 and 173, as shown in Fig. 38. The arm 186 remains in this position until the knot is completed and stripped, and is then returned to its initial position, wherein it is out of the way of the next reserve thread as the winder-tending mechanism advances.

As soon as the exhausted thread is in position at the knotter, the clamping finger 181 (Fig. 37) clamps the exhausted and the reserve threads, but not so tightly as to prevent the threads from slipping past it to provide slack for the rotating tying-bill. As soon as the finger 181 has clamped the 125 threads, the member 176 is moved to release the reserve thread at that point.

As indicated in Fig. 38, one of the functions of the plate 192 is to clamp the threads between the plates 172 and 174 in

order to form an abutment for the stripping action of the disk 162.

As the threads are clamped by the finger 181, the strand extending to the tube is 5 severed by a shear comprising an arm 193 (Fig. 41) fixed to the lower end of a vertical shaft 194, said shaft being rocked by means of an arm 195 (Figs. 39 and 40) and a cam groove 196 in the disk 190. The arm 193 10 has fixed thereto a shear blade 197 (Fig. 51) between which and the edge 198 (Fig. 49) of the hook 181^a the thread is sheared. A guard plate 199 is fixed to the arm 193 to prevent the strand that extends to the cheese 15 from coming in contact with the shear blade 197. The length of thread above the shear 197 198 is drawn into the tube 101. After the shear has acted, the screen 155 is swung aside to allow the upper part of the severed 20 thread to pass through the tube 101. Said shear provides a uniform length of thread to be operated upon by the knotter and to be disposed of by the suction tube 102.

The operation of the knotter is similar to 25 that described in Patent No. 959,592 and need not be here set forth. The thread-ends sheared off by the tying-bill are withdrawn by the exhaust current in the tube 102, the clamp member 181 having been moved to release the threads as the knot is completed.

In the tube 102 is a slide valve 200 (Fig. 34) reciprocated to open and close the tube by means of an arm 201 pivoted at 202, a link 203 connecting the arm to the valve, 35 and a roll on the arm traveling in the groove of a cam 204 on the shaft 92. The valve is opened when the tying-bill begins operating, and is closed after the clipped-off thread-ends have been removed through the 40 tube 102.

It will be remembered that the cheese was rotated by the roll 125 in the direction to unwind yarn, in order to furnish slack as the arm 131 draws the thread down to the 45 knotter. To stop such unwinding after the threads have been positioned in the knotter, I provide a plate 205 (Figs. 20, 44 and 45) aligned with the rolls 118 and 125 and fixed to an arm 206 secured to a rock shaft 207. Said shaft is rocked by a cam 208 and an arm 209 attached to the shaft, the cam being 50 mounted on the shaft 145. As the threads are being positioned in the knotter, and as the roll 125 is passing out from under the cheese, the plate 205 is raised to lift the cheese off said roll and thus stop the rotation of the cheese.

Referring to Figs. 22, 48 and 49: it is 55 desirable to minimize the extent to which the traveling mechanism carries along the portion of the thread extending from between the cheese and the roll 125 and plate 205, since that portion of the thread might otherwise slip out from between the cheese 60 and the roll or plate. I therefore provide

a hook 210 arranged to engage the strand extending from the cheese and to move said strand rearwardly through the passageway formed by the members 132 133, at a speed sufficient to compensate for the forward feed 70 of the traveling mechanism. Said hook is fixed to a rack-bar 211 which is slidable in a guideway 212, the rack-bar being reciprocated by means of gear wheels 213 214, sector 215, arm 216 and cam 217, the cam 75 being fast to the shaft 92.

The knot having been completed, slack in the united threads is taken up by means of a roll 218 fixed on a shaft 219, onto which roll the cheese is dropped by the plate 205. 80 This roll is rotated in the direction to wind yarn on the cheese, by means of a train of gears 220 221 222 223 224 connecting the shafts 127 and 219 (Fig. 45). The winding up of the slack yarn draws the thread taut, 85 pulling it to the left (Fig. 22) toward the vertical plane passing through the cheese and the reserve bobbin, but the thread does not clear the hook on the arm 131 until said arm in its upward movement leaves the 90 thread. When the arm 131 leaves the thread, further slack is thereby thrown into the thread, which slack is taken up by the continued rotation of the cheese under the 95 action of the roll 218.

To insure that the thread shall leave the bridge 53 while the slack-take-up roller 218 is rotating the cheese, an arm 218^a (Figs. 17 and 18) is fixed in the framework 72 in position to pass just below said bridge, so as 100 to push off the thread if for any reason it had not theretofore left the bridge.

To keep the united threads in the vertical plane of the unit as the traveling mechanism progresses, there is provided a chain 105 225 (Fig. 49) running at a rate equal to the rate of travel of the said mechanism, over sprocket wheels 226 227 (Fig. 33), the latter being fixed on a shaft 228 which is driven from the shaft 145 through spiral gearing 110 229. The forward run of the chain 225 parallels the passageway formed by the members 132 133, said chain carrying lugs 230 that pick up the thread brought back by the hook 210 and move the thread along 115 to the rear end of the plate 132. There the thread is picked up by lugs 231 on a chain 232 (Figs. 20 and 49) running over sprocket wheels 233 234, the wheel 233 being secured to the shaft 228. The forward run of the 120 chain 232 is inclined rearwardly so as to allow the thread gradually to approach the cam 2, said chain keeping the thread out of contact with the cam 2 until after the cheese 125 has been deposited on the cam and has been accelerated.

When the roll 218 has caused slack in the united threads to be taken up, a cam 235 (Figs. 18 and 20) fixed to the framework 130 of the traveling mechanism is carried under

the lever 8 and swings said lever up and over its center, whereupon the lever drops toward its operative position, the cheese falling onto a shelf or plate 236 fixed to the frame members 114 in a horizontal plane just above the cams 2. Prior to the commencement of action of the cam 235, the cam 111 swings the lever-arm 37^b (Fig. 8) back so that it shall not be struck by the projection 40 when the lever 8 is swung over as just described. By reference to Fig. 18, it will be evident that after the cheese has passed a certain point in its travel from the slack-take-up roller 218 to the cam drum 2, the distance between the cheese and the bobbin will be decreasing. To prevent the thread from becoming slack while the cheese is thus approaching the bobbin, I provide suitable means, as, for example, a curved plate 237 (Figs. 18 and 21) hinged at 238, with which plate the cheese makes peripheral contact as the cheese approaches the bobbin, whereby the cheese is rotated in the direction to take up slack. If the plate 237 were not provided, it will be evident that the cheese would be free to revolve in the reverse or unwinding direction throughout the period during which the cheese is passing from the slack-take-up roll 218 to the shelf 236. Such reverse rotation is, of course, prevented while the cheese is in contact with the plate 237. While the winder-tender is passing around the ends of the winder framework, the lower end of the plate 237 rests upon the shelf 236, as indicated in Fig. 17. To the rear end of the plate 236 is fixed an extension 239 which is thinner than the plate 236 so as to allow the cheese to lie as close as possible to the rapidly rotating cam 2 before the cheese drops onto the cam. (See Fig. 52.) In order that the cheese shall rest lightly on the cam 2 until the cheese has attained a sufficient speed of rotation, I provide a bar 240 supported by arms 241 fixed to a shaft 242 (Figs. 17, 18 and 52). A spring 243 acting on a crank arm 244 tends to rock said shaft in the direction to depress the bar 240. Before the extension 239 has passed out from under the cheese, the end 8^a of the lever 8 has passed under the beveled end of the bar 240, whereby the tension of the spring 243 is applied to counterbalance a portion of the weight of the lever and cheese, so that the latter shall rest lightly on the cam 2. (See Fig. 5.)

245 (Fig. 17) is a stop fixed on the shaft 242 and arranged to contact the adjacent portion 246 of the framework of the traveling mechanism to limit the action of the spring 243.

As shown in Fig. 52, the arm 244 and the spring 243 are so arranged that the leverage of the spring is greater when the bar 240 is 65 in engagement with a lever that supports a

cheese of large diameter than when bearing against a lever that carries a smaller cheese, the counterbalancing effect being thus proportioned to the weight of the cheese.

A moment before the bar 240 passes off the lever-arm 8^a, the chain 232 has deposited the thread on the angular upper end 247 (Figs. 21 and 33) of a finger 248, which finger is fixed to a shaft 249. Said shaft is swung toward the cam 2, to lay the thread lightly on said cam, by a torsion spring 250, and is restored to its initial position by a cam 251 acting upon a roll carried by a crank arm 252 fixed to the shaft 249. The cam 251 is driven from the shaft 145 through the medium of gears 253.

The means for resetting the detector and throw-out mechanism comprises a cam bar 254 (Figs. 18 and 43) extending longitudinally in the framework of the traveling mechanism. At the forward end of said bar is a shoulder 255 which engages a pin 256 fixed to the rock shaft 61, said pin being substantially in the position indicated in Fig. 9 before said shoulder contacts it. As the cam bar passes said pin, the shoulder 255 causes the shaft 61 to turn to the position shown in Fig. 11; and then a shoulder 257 on the bar 254 strikes the pin 66 fixed to said shaft 61 and turns said shaft into the position represented in Fig. 12. The turning of the shaft 61 brings the detector finger 63 into position to allow the new thread to pass into the guideway formed by the wire 59 and the plate 59^a. Such movement of the shaft also causes the bent finger 258 to follow the link 30 as the latter swings by gravity toward its normal position, thus preventing said link from swinging back and forth. The parts of the detector mechanism stand in the position shown in Fig. 12 from the time the shoulder 257 acts until the cam bar 254 passes the pin 66. Before said cam bar has passed, the finger 248 has deposited the thread on the cam 2, said thread passing into the guideway formed by the parts 59 59^a. In returning to its operative position the detector finger 63 moves step by step so as not to strike the thread with undue momentum. As the cam bar leaves the pin 66, the detector finger 63 swings toward the thread, pausing a moment near the thread as the pin 256 strikes a projection 254^a on the cam bar 254.

As indicated in Fig. 22, the winder-tending mechanism performs different operations upon several units at the same time.

In order to insure that each unit shall be in thrown-out condition before the winder-tending mechanism reaches it, I provide a suitable feeler mechanism, as, for example, a rod 259 (Fig. 21) having a head 260 at its forward end, said rod being slidable in bearings in the frame-members 114. The head 260 is supported so that in the travel of 130

the winder-tending mechanism, said head shall contact a suitable portion of any unit in operative position, as for instance, the tube *c* (see Fig. 18). The stoppage of the head 260 against the tube is arranged to cause a stoppage of the travel of the winder-tending mechanism. As herein shown, relative movement between the rod 259 and the traveling mechanism causes a knife switch 261 (Figs. 21 and 21^a) to open, the movable member of the switch being connected to said rod by a link 262. Said switch is included in the circuit of the motor 76. It will be seen that if for any reason a cheese has not been thrown out before the traveling mechanism reaches it, said mechanism will be stopped.

When the cheeses reach a predetermined diameter, they are removed by the operator and replaced with tubes having a small quantity of yarn thereon, the tubes in practice never being wholly emptied. In order that the operator may be notified when a cheese has reached a predetermined size, I provide suitable means such as a feeler or gage arranged to stop the travel of the winder-tending mechanism when the latter arrives at a complete cheese. In this embodiment the gage or feeler consists of a finger 263 (Figs. 17, 18 and 19) having an inclined plate 264 at its outer end arranged to contact the periphery of a cheese. The finger 263 is fixed to one end of a shaft 265 supported in a bracket 266. To the other end of the shaft is fixed a crank arm 267 which is connected by a link 268 to a pin 269 (Fig. 18^a) slideable in a suitable guide 270. Said pin normally retains in closed position the movable element 271 (Figs. 17, 17^a and 18) of a switch connected into the motor circuit, a spring 272 operating to open the switch whenever the pin 269 is withdrawn from engagement with the member 271. The feeler 263 is yieldingly held in its normal position by a spring 273 (Fig. 18.) If desired, means may be provided to limit the withdrawing movement of the pin 269, such as a stop 274 (Figs. 17^a and 18) on the shaft 265 arranged to engage the bracket 266. When the inclined end 264 of the feeler 263 is carried against a full-size cheese, said feeler is swung to withdraw the pin 269 from the switch element 271, whereupon the spring 272 opens the motor circuit and suspends the travel of the winder-tending mechanism. The operator then replaces the cheese with a tube *c*, and closes the switch.

The mode of operation is as follows: When any one of the active threads is exhausted, either by the running out of all of the thread on the corresponding active bobbin or by the breakage of said thread, the corresponding detector finger 63 is moved by its spring 65 from the position shown in

Figs. 5 and 7 to that shown in Figs. 8 and 10. This movement of the detector finger results in a corresponding movement of its connected finger 66 which acts upon the link 30 suspended from the lever 8 that supports the yarn mass *d* whose active thread has just been exhausted, and thereby moves said link to the position shown in Fig. 8. The link 30 is thus brought into the path of the corresponding constantly vibrating hook 31 and this hook in its descent engages the link and pulls it downwardly. The effect of this downward pull is to swing the yarn-mass-carrying lever 8 from the position shown in Fig. 8 to a position sufficiently forward of its axis to cause the yarn mass to drop by gravity to the position shown in Fig. 9. The effect of this movement of the yarn mass is to remove it from the winding action of the driving cam drum 2 so that the winding movement of the container *c* ceases. Usually, after the exhaustion of an active thread has been detected, the winding continues until all of the active thread has been wound upon the yarn mass *d*. The descent of the yarn mass to the position shown in Fig. 9 suffices, through the swing of its lever 8 and the action of the stationary fulcrum projection 69 (Fig. 9), to move the lower end of the link 30 beyond the reach of the corresponding vibrating hook 31.

The organization and timing of the machine is such that, under ordinary working conditions, each active thread will have become exhausted before the winder-tender in its travel reaches it. The winder units therefore are operated upon by the winder-tender in regular succession. When the winder-tender reaches the position of a yarn mass whose thread has become exhausted, the cam 110 on the cam bar 109 (Figs. 9, 18, 21, and 43) lifts the outer end 37^a (Fig. 9) of the lever 37, thereby relieving the yarn mass lever 8 from the tension of the spring 39 and this action of the cam bar 109 continues until some time after the tying has been completed. Immediately following this, the cam 116 (Figs. 9 and 21) of the traveling carriage encounters the arm 8^a of the yarn mass carrying lever 8 and depresses it, thereby lifting the yarn mass *d* to the position shown in dotted lines at the right of Fig. 22, the yarn mass in this position being above the plane of the co-acting parts on the traveling carriage of the winder tender. As the carriage advances its end-finding roll 118 comes beneath the yarn mass and the dwell 117 of the cam 116 then passes forwardly beyond the arm 8^a whereupon the yarn mass drops to the level shown in dotted lines at the middle of Fig. 22, resting upon the roll 118.

The end-finding roll 118 rotates in the direction to unwind the yarn. As the carriage continues to advance, the mouth or

opening of the suction tube 101 (Fig. 22) passes beneath the reversely rotating yarn mass. In the further advance of the traveling carriage the yarn mass is rotated 5 reversely by the roll 125 (Figs. 22, 25 and 31) as it leaves the roll 118. Hence, during the entire passage of the suction opening beneath the yarn mass said yarn mass is rotated in the unwinding direction. The con- 10 joint action of the unwinding rolls 118 and 125 and the suction is to pick off from the yarn mass the end of the exhausted thread. This thread end is sucked into the opening of the suction tube 101 which acts as a suction 15 clamp to hold on to the end of the wound thread. When, in the travel of the carriage the suction opening passes beyond the yarn mass, the end of the thread extending from the yarn mass enters the notch 108 (Figs. 31 20 and 32) at one side of the suction nozzle and extends therefrom to the yarn mass and in front of the notch 130 of the swinging transfer arm 131. Thereupon, said arm 131 swings from the position shown in Fig. 32 25 to that shown in Figs. 18 and 33. During this swing the exhausted thread is drawn out into a loop as the conjoint result of the continued backward rotation of the yarn mass and the transfer arm 131 drawing 30 upon the thread held by the suction. As shown in Fig. 33, the exhausted thread extending from the yarn mass passes over guides 132 and 133 down to the notch 130 of the transfer arm 131; whereas the yarn 35 from the suction opening passes from the notch 108 through the notch 131^a (Figs. 33 and 41) and thence downwardly over the finger 192^a (Figs. 33 and 35) of the notched plate 192 of the positioning arm 186, and 40 thence to the notch 130 of the transfer arm 131. By this time the advance of the tender carriage has brought the knotter 161 and the neighboring flaring thread guides 169, 171 and 173 (Figs. 34, 36, 37, 38 and 53) 45 close to the corresponding reserve thread that is held in the appropriate clamp 49, 50, (Figs. 5 and 7) and lies against the corresponding bridge 53. The further advance of the tender carriage causes the flaring 50 thread guides 169, 171 and 173 to straddle the reserve thread and direct the same within reach of the clamp 176 (Figs. 36 and 38) and the clamp 181 (Figs. 37 and 38). The clamp 176 then closes, clamping the end of 55 the reserve thread close to the inlet of the suction tube 102 (Fig. 38); and the reserve thread is released from the clamp 49, 50 by the finger 175 (Figs. 5, 7, 36, 38 and 53). A moment thereafter, the positioning arm 60 186 swings from the position shown in Figs. 33 and 35 to that shown in Figs. 38 and 53. During this movement of the swinging arm 186, the notches in its two plates 191 and 192 (Fig. 35) engage one strand of the exhaust- 65 ed thread extending from the yarn mass *d*

and carry said strand into the flaring guides 169, 171 and 173 and into coöperative relation with the knotter as shown in Figs. 38 and 53, thus completing the transfer of the end of the exhausted thread from the wound 70 yarn mass into coöperative relation with the knotter. The above described movement of the swinging arm 186 causes both threads to be tightly clamped between the bracket 172 and the plate 174 (Fig. 38) between which 75 the said thread is pressed by the plate 192. A moment later, the clamp 181 yieldingly 80 clamps both threads, and the clamp 176 opens. At this stage of the operation the shear 197 (Fig. 51) on the swinging arm 193 (Fig. 41) acts to cut the extending end 85 of the exhausted thread close to the notched guide 131^a and hence between the suction tube 101 and the clamp 181. The cut-off end of the thread is withdrawn by the suction tube and conveyed to the centrifugal separator 98 (Figs. 17 and 46), an end of uniform length being left between the cutter 197 and the knotter. The knotter then acts 90 to tie the two threads together and to cut off the ends of the two threads so as to leave short ends of threads at the knot. When the waste ends are released by the clamp 181 95 they are drawn into the suction tube 102 and conveyed to the centrifugal separator by the air current. In the meantime, the advance of the traveling tender carriage has carried the reversely-rotating roll 125 (Fig. 22) beyond the yarn mass *d* and has brought 100 the plate 205 into position beneath the yarn mass, said plate being then lifted to the position shown in Figs. 22, 33, and 44, thereby stopping the rotation of the yarn mass.

During the action of clamping the two threads into operative relation to the knotter, and during the action of the knotter, the tender carriage continues to advance. In order to maintain the thread extending from the yarn mass in proper relation thereto, the hook 210 (Figs. 22 and 49) engages 105 the thread between the yarn mass and the knotter, and, since said hook then travels backwardly upon the tender carriage as fast as the tender carriage advances, the thread extending from the yarn mass is maintained 110 in proper relation thereto.

After the knotting has been completed, the advance of the tender carriage brings the rotating roll 218 (Fig. 22) beneath the yarn mass. This roll 218 rotates in the direction 115 to wind the yarn upon the container *c*, thereby by taking up the slack in the now knotted threads between the yarn mass and the reserve bobbin which has now become the active bobbin.

The further advance of the tender carriage brings the cam 235 (Figs. 9, 18, 20 and 21) beneath the lever 8 carrying the yarn mass, thereby lifting said yarn mass far enough 120 over the axis of the said lever to permit said 125

yarn mass to drop upon the shelf 236 (Fig. 20) on the traveling tender carriage, which shelf is located just above the plane of the tops of the driving cam drums 2.

As the carriage thereafter advances and before the yarn mass passes off the shelf 236 on to the driving cam drum 2, the extending end 8^a of the lever 8 passes beneath the spring-tensioned bar 240 (Figs. 5, 17, 18 and 21), whereby a portion of the weight of the yarn mass is sustained so that the yarn mass bears lightly upon the driving cam drum 2 as the shelf 236 passes from beneath the yarn mass. The further advance of the traveling tender carriage carries the bar 240 beyond the lever extension 8^a and shortly thereafter the cam bar 109 (Figs. 18, 20 and 43) passes beyond the lever 37 so that the full weight of the yarn mass augmented by the tension of the spring 39 rests upon the driving cam drum 2. It will be seen that the counterbalancing bar 240 and the pressure-relieving bar 109 constitute means for insuring that the cheese shall be gradually accelerated to full winding speed before the tension of the spring 39 is applied to the cheese.

During the taking up of slack in the united threads and during the restoration of the yarn mass to the winding position, the thread leading from the yarn mass to the supply bobbin is maintained in proper relation to the yarn mass by means of the traveling chains 225 and 232 (Figs. 20 and 49) whose co-acting runs travel in opposite direction to the forward feed of the tender carriage, and at the same speed.

Just before the bar 240 passes beyond the lever arm 8^a the chain 232 deposits the thread upon the end 247 of the finger 248 (Figs. 20, 21 and 33) and said finger swings toward the driving cam drum 2 so as to lay the thread lightly against said drum, the thread passing into the guideway formed by the parts 59, 59^a. The detector finger 63 has previously been swung from the position shown in Fig. 10 to that indicated in Fig. 12, by the action of the cam bar 254 (Figs. 10 and 43) on the pins 256 and 66. After the thread has entered said guideway, the detector finger 63 is swung into contact with the thread by the spring 65, the action of the spring being controlled by said cam bar so that the finger shall not strike the thread with excessive force.

As indicated by the several yarn masses shown by dotted lines in Fig. 22, the various instrumentalities mounted on the traveling tender carriage are acting concurrently upon several yarn masses.

The attendant of the machine removes the empty bobbins from their holders; inserts full bobbins, places their thread ends in the appropriate clamps 49, 50; and removes the completely wound yarn masses and their containers and replaces them by containers

having a small amount of yarn thereon. Otherwise the action of the machine is entirely automatic.

The machine is thus an automatic machine capable of receiving a large number of active and reserve bobbins or other thread carriers, and the machine acts automatically when needed to tie a reserve thread to a thread extending from a wound yarn mass.

While the present embodiment of the invention has been described with considerable particularity, I would have it understood that the invention is not limited to the mechanisms and arrangement of mechanisms herein set forth.

The winder-units, including the cam drums 2, the detecting mechanism, and the mechanism for throwing out the cheeses, are claimed in application Ser. No. 5,563, filed Feb. 1, 1915. The yarn carrier *c* is claimed in application Serial No. 74,289, filed Jan. 26, 1916. The means for supporting and locking the yarn carrier *c* is claimed in application Serial No. 74,290, filed Jan. 26, 1916.

In certain of the following claims I have, for the sake of brevity, used the general term "a winding couple" to indicate two yarn masses, one of which is being unwound onto the other, without regard to the form or location of such masses.

I claim as my invention:

1. A winder having, in combination, a mechanism for winding a thread, means for detecting the exhaustion of said thread, and means for joining to said exhausted thread a reserve thread.

2. A winder having, in combination, a mechanism for winding a plurality of threads; means for supporting active threads and reserve threads; means for detecting an exhausted active thread; and means for joining a reserve thread to such exhausted thread.

3. A winder having, in combination, a plurality of units arranged side by side, each unit comprising a rotatory drum having a yarn-traversing groove in its periphery, means for supporting a yarn-mass in contact with the periphery of the drum, and means for removing the yarn-mass from contact with the drum; and means arranged to travel along the row of units for restoring the yarn-masses into contact with the drums.

4. A winder having, in combination, a row of reserve-thread holders, a knotter comprising a tying bill and arranged to travel in a path parallel to the row of reserve-thread holders, the tying-bill being supported so as to be carried against successive threads in said holders, and means for moving exhausted threads into said tying-bill.

5. A winder having, in combination, a

- plurality of units arranged side by side, each unit comprising a rotatory drum having a yarn-traversing groove in its periphery, a lever pivoted to swing in a vertical plane and arranged to support a yarn-mass in contact with the periphery of the drum, and means for swinging the lever to remove the yarn-mass from contact with the drum; and means arranged to travel along the row of units for swinging said levers to restore the yarn masses into contact with the drums. 5
6. A winder having, in combination, a plurality of units arranged side by side, each unit comprising a rotatory drum having a yarn-traversing groove in its periphery, a lever pivoted to swing in a vertical plane and arranged to support a yarn mass in contact with the periphery of the drum, and means automatically actuated upon the exhaustion of the thread being wound for swinging said lever to remove the yarn mass from contact with the drum; and means arranged to travel along the row of units for restoring the yarn masses into contact with the drum. 10
7. A winder having, in combination, a plurality of units arranged side by side, each unit comprising a rotatory drum having a yarn-traversing groove in its periphery, a lever pivoted between its ends and arranged at one end to support a yarn mass in contact with the periphery of the drum, a member attached to the other end of said lever, an oscillatory hook adapted to engage said member to swing said lever to remove the yarn mass from contact with the drum, means withheld from action by the thread being wound for moving said member into operative relation to said hook; and means arranged to travel along the row of units for swinging said levers to restore the yarn masses into contact with the drums. 15
8. A winder having, in combination, a plurality of units arranged side by side, each unit comprising a yarn-mass rotating means, a lever pivoted to swing in a vertical plane and arranged to support a yarn mass in contact with said rotating means, and means for swinging said lever to remove the yarn mass from contact with the drum; and a cam arranged to travel along the row of units below the plane occupied by the thrown-out levers for restoring said levers to place the yarn masses in contact with the rotating means. 20
9. A winder having, in combination, a plurality of units arranged side by side, each unit comprising a rotatory drum having a yarn-traversing groove in its periphery, a lever pivoted between its ends and arranged at one end to support a yarn mass in contact with the periphery of the drum, means withheld from action by the thread being wound for swinging said lever to place the yarn mass at the opposite side of the pivot of said lever; and means arranged to travel along the row of units and provided with a cam arranged to swing said levers to return the yarn masses into contact with the drums. 25
10. A winder having, in combination, mechanism for winding a plurality of threads from one sort of container to another sort of container; means for supporting active threads and reserve threads; and a knot-tying mechanism for joining a reserve thread to an exhausted active thread. 30
11. A winder having means for rotating a yarn mass, a movable member for supporting a yarn mass in contact with said rotating means, devices for moving said member to place the yarn mass into and out of operative relation to the rotating means, and means to regulate the degree of pressure between the rotating means and the yarn mass. 35
12. A winder having, in combination, means for rotating a yarn mass, a lever pivoted to swing in a vertical plane and arranged to support a yarn mass in contact with said rotating means, devices for swinging said lever to move the yarn mass into and out of contact with the rotating means, and means for cushioning the movement of the yarn mass into contact with the rotating means. 40
13. A winder having, in combination, a plurality of units arranged side by side, each unit comprising a rotatory drum, means for supporting a yarn mass in contact with the periphery of the drum, and means for moving the yarn mass out of contact with the drum; and means arranged to travel along the row of units and comprising a yarn-mass support mounted to move in a path close to the peripheries of the drums, said traveling further comprising means to place a thrown-out yarn mass on said support. 45
14. A winder having, in combination, a plurality of units arranged side by side, each unit comprising a rotatory drum, a lever pivoted to swing in a vertical plane and arranged to support a yarn mass in contact with the periphery of the drum, and means to swing the lever to remove the yarn mass from contact with the drum, and means arranged to travel along the row of units, said traveling means comprising a yarn-mass support arranged to move in a plane close to the peripheries of the drums, a cam for swinging the lever to place the yarn mass on said support, and means engaging said lever to partially counterbalance the weight of the yarn mass for a time after said yarn-mass support has been moved out from under the yarn mass. 50
15. A winder having, in combination, a

- mechanism for winding a plurality of threads; means for supporting active threads and reserve threads; and means movable into proximity to said reserve threads for joining a reserve thread to an active thread when said active thread becomes exhausted.
16. A winder having, in combination, a mechanism for winding a thread from one sort of container to another sort of container; means for holding a reserve thread; a thread-uniting means; and means for recurrently moving said thread-uniting means into proximity to said threads.
17. The combination, with a winder having yarn-mass carrying members, of a traveling mechanism for acting upon the yarn masses, said mechanism including means for moving the members to position the yarn masses with relation to the traveling mechanism.
18. The combination with a winder having yarn-mass carrying levers, of a traveling mechanism for acting upon the yarn masses, said mechanism including means to lift the levers to position the yarn masses with relation to the traveling mechanism.
19. The combination, with a winder comprising yarn-mass carrying levers, of a traveling end-finder, and means moving with said end finder for moving the levers to position the yarn masses with relation to the finder.
20. The combination, with a winder comprising yarn-mass carrying levers, of a traveling end-finding mechanism comprising a rotary roll and a suction tube adjacent to said roll, and means moving with said end-finding mechanism for raising successive levers and then permitting them to drop to place the yarn mass on said roll.
21. The combination, with a winder comprising yarn-mass carrying levers pivoted between their ends, of a traveling end-finding mechanism comprising a rotatory roll and a suction tube located adjacent to said roll, and a cam traveling with the end-finding mechanism and arranged to act upon one end of successive levers to raise the opposite end of the lever, the passage of the cam permitting the elevated end of the lever to drop to deposit the yarn mass on said roll.
22. In a winder-tending mechanism, the combination of end-finding means; a knotter; and means for placing the found thread on the knotter.
23. In a winder-tending mechanism, the combination of end-finding means; a knotter; a pivoted arm adapted to engage the found end and carry it to a point near the knotter; and means for moving the found end from said point into the knotter.
24. In a winder-tending mechanism, the combination of end-finding means; a knotter; means for moving the found end to a point near the knotter; and a pivoted arm arranged to carry the thread from said point into the knotter.
25. In a winder-tending mechanism, the combination of end-finding means; a knotter; a pivoted arm arranged to carry the found end to a point near the knotter; and an arm mounted to swing upon an axis extending in a direction different from the direction in which the axis of the first mentioned arm extends, for moving the found end from the point to which it is carried by the first mentioned arm into the knotter.
26. In a winder-tending mechanism, the combination of end-finding means adapted to hold the found end; a knotter; an arm arranged to swing against the found thread and carry a bight thereof to a point near the knotter; and a pivoted arm arranged to engage one strand of the bight and carry said strand into the knotter.
27. In a winder-tending mechanism, the combination of means for holding the end of a thread; a knotter; means for carrying a bight of the thread to a point near the knotter; and means for carrying a strand of said bight into the knotter.
28. In a winder-tending mechanism, the combination of means for finding a thread-end on a yarn mass; a knotter; means for moving the found thread to the knotter; and means for rotating the yarn mass to furnish slack to said moving means.
29. In a winder-tending mechanism, the combination of means for finding and holding a thread-end on a yarn mass; a knotter; means for pulling a bight of the found thread to the knotter; and means for rotating the yarn mass to furnish slack to said pulling means.
30. In a winder-tending mechanism, adapted to act upon a yarn mass wound upon a container, the end of the thread being wrapped around the container beside the yarn mass, the combination of means for picking up said thread; and means for severing it at a point between said picking-up means and the container.
31. In a winder-tending mechanism adapted to act upon a yarn mass wound upon a container, the end of the thread being wrapped about the container beside the yarn mass, the combination of an air tube for picking up said thread; and a shear arranged to move over the mouth of said air tube to sever said thread between the air tube and the container.
32. In a winder-tending mechanism adapted to act upon a yarn mass wound upon a container, the end of the thread being wrapped about the container beside the yarn mass, the combination of an exhaust air tube for picking up a bight of said

thread; and a shear arranged to be moved over the mouth of said tube to sever the strand of the bight which leads to the container.

33. In a winder-tending mechanism adapted to act on a yarn mass formed upon a container, the end of the thread being wrapped about the container beside the yarn mass, the combination of an exhaust air tube for picking up a bight of said thread; a shear blade reciprocable into and out of position over the mouth of said tube and through said bight; and a shear blade coöperating with the other shear blade to sever one strand of the bight.

34. In a winder-tending mechanism, the combination of a knotter; a rotatory roll arranged to be contacted by a yarn mass and to rotate the latter; an exhaust air tube having its mouth located adjacent to one end of said roll for picking up and holding the thread end on the yarn mass; means for moving a bight of the thread to the knotter; and a rotatory roll alined with the first mentioned roll for rotating the yarn mass to furnish slack to said thread-moving means.

35. In a winder-tending mechanism, the combination of means for finding a thread end on a yarn mass; a knotter; a rotatory roll adjacent to said end-finding means; and an arm arranged to swing from a point between the end-finding means and the roll to a point near the knotter for transferring the found thread to the latter point, said roll rotating the yarn mass to furnish slack to said arm.

36. In a winder-tending mechanism, the combination of means for finding a thread end on a yarn mass; a knotter; means for moving the found thread to the knotter; means for rotating the yarn mass to furnish slack to said moving means; and means for suspending the rotation of the yarn mass when the thread has been placed in the knotter.

37. In a winder-tending mechanism, the combination of means for finding a thread end on a yarn mass; a knotter; means for moving the found thread to the knotter; a roll alined with the end-finding means for rotating the yarn mass to furnish slack to said moving means; and a member alined with said roll for lifting the yarn mass off said roll to arrest the rotation of the yarn mass after the thread has been placed in the knotter.

38. The combination of two driven rolls arranged for peripheral contact with a yarn mass for rotating such mass, and means for bodily transferring the yarn mass from one roll to the other.

39. The combination of a means for rotating a yarn mass; a roll for rotating the yarn mass to take up slack in the thread;

and means for moving the yarn mass from contact with said roll into contact with the first mentioned rotating means.

40. The combination of a pivoted lever having a pivot for a yarn mass; two separate means for rotating the yarn mass; and means for swinging said lever to transfer the yarn mass from one rotating means to the other. 70

41. The combination of a pivoted lever having a pivot for a yarn mass; a rotatory drum arranged to rotate the yarn mass through peripheral contact with the latter; means for pivotally moving said lever to place the yarn mass upon the periphery of 85 the drum; and means for laying upon the drum the thread extending to the yarn mass.

42. The combination of a pivoted lever having a pivot for a yarn mass; a rotatory drum arranged to rotate the yarn mass 85 through peripheral contact with the latter; means for pivotally moving the lever to place the yarn mass upon the periphery of the drum; a pivoted finger to receive the thread extending to the yarn mass; and 90 means for pivotally moving said finger to lay the thread on the periphery of the drum.

43. In a winder-tending mechanism, the combination of means for tying a knot in a thread extending to a yarn mass; means for 95 causing said tying means to travel in one direction with relation to the yarn mass; and means traveling with the tying means for moving a portion of the thread in the opposite direction to maintain said portion 100 in a relatively constant relation to the yarn mass.

44. In a winder-tending mechanism, the combination of means for tying a knot in a thread extending to a yarn mass; means for 105 causing said tying means to travel in one direction with relation to the yarn mass; and a reciprocatory hook traveling with said tying means and adapted (upon its movement in the direction opposite to the traveling movement) to engage said thread at a point between the tying means and the yarn mass.

45. The combination of a winder unit and mechanism arranged to travel past said unit 115 to unite the exhausted and a reserve thread, said mechanism comprising means for keeping the united threads in the vertical plane of the unit.

46. The combination of a winder unit and a traveling mechanism for uniting an exhausted and a reserve thread and an endless conveyer adapted to engage the united thread, said conveyer operating in a direction contrary to the direction of travel of 125 said mechanism.

47. The combination of a winder unit and a traveling mechanism for uniting an exhausted and a reserve thread, and comprising 130 an endless conveyer adapted to engage

the united threads, said conveyer operating in a direction contrary to the direction of travel of said mechanism and being inclined toward a portion of the unit so as to permit 5 the thread gradually to approach said portion.

48. The combination of a winder comprising a plurality of units, an endless supporting means extending adjacent to said units 10 and a winder-tending mechanism arranged to travel upon said supporting means and operate upon said units.

49. The combination of a plurality of winder units arranged in a row, each unit 15 comprising two bobbin holders, yarn-mass supporting means, yarn-mass rotating means, and a reserve thread-end holder, supporting means extending along said row of units, and means for operating on said units, 20 said operating means being mounted on said supporting means for movement along the row of units.

50. The combination of a plurality of winder units arranged in a row, each unit 25 comprising two bobbin holders, yarn-mass supporting means, yarn-mass rotating means, and a reserve thread-end holder; supporting means extending along said row of units; and means for operating on said 30 yarn-mass supporting means and reserve thread-end holders, said operating means being mounted on said supporting means for movement along the row of units.

51. The combination of a plurality of 35 winder units arranged in a row, each unit comprising two bobbin holders, yarn-mass supporting means, yarn-mass rotating means, and a reserve thread-end holder; supporting means extending along said row 40 of units; a framework mounted on said supporting means for movement along the row of units; a knot-tying mechanism located on said framework in position to be carried into operative relation with the successive 45 thread-end holders; mechanism on said framework for finding an end on a yarn mass; mechanism on said framework for carrying the found end to the tying mechanism; and means on said framework for operating upon said yarn-mass supporting 50 means.

52. The combination of a winder comprising a plurality of units arranged in a row, supporting means extending longitudinally of the row of units, a frame-work 55 mounted for traveling movement upon said support, mechanisms carried by said frame-work for operating upon said units, said mechanisms including exhaust air apparatus comprising an exhauster supported upon 60 said frame-work forwardly of the units, and a motor located upon said frame-work forwardly of the units for driving said mechanisms.

65 53. A winder having in combination,

means for supporting two bobbin threads; means for winding one of said threads from its bobbin onto another sort of container; a knot-tying mechanism movable into position adjacent to said other thread; and 70 means for actuating said mechanism to unite said threads.

54. In a winder-tending mechanism, the combination of end-finding means, a knotter, means for placing the found end in the 75 knotter, and means for severing the thread at a point between the knotter and the end-finding means.

55. In a winder-tending mechanism, the combination of end-finding means, a knotter, so 80 means for moving a bight of the thread to a point near the knotter, means for moving a strand of the bight into the knotter, and means for severing said strand at a point between the knotter and the end-finding means. 85

56. In a winder-tending mechanism, the combination of an exhaust air tube for holding one end of a thread, a knotter, means for moving a bight of the thread to 90 a point near the knotter, means for moving a strand of the bight into the knotter, and means for severing said strand at a point between the knotter and the air tube.

57. In a winder-tending mechanism, the combination of means for holding the end of 95 a thread, a knotter, a pivoted arm adapted to swing against the thread and carry a bight of the thread to a point near the knotter, a hook into which one strand of the bight is carried during the movement of 100 said arm, means for moving said strand into the knotter, and a shear blade coöperating with said hook to sever said strand.

58. In a winder-tending mechanism, the combination of an exhaust air tube for receiving the end of a thread, a knotter, means for drawing said thread toward the knotter, and withdrawable means for preventing said 105 thread from passing too far into said tube.

59. In a winder-tending mechanism, the 110 combination of an exhaust air tube for receiving the end of a thread, a knotter, means for moving said thread toward the knotter, and a screen within said tube and arranged to be swung into and out of position to obstruct the passage of the thread through said tube. 115

60. The combination of a knotter, an exhaust air tube located with its mouth near the knotter, said tube serving to carry off the 120 thread ends sheared by the knotter, means for positioning a thread at the knotter, and means for interrupting the air current in said tube while said positioning means is acting.

61. The combination with a winder, of means traveling along the winder, for detecting yarn-masses of predetermined size.

62. The combination, with a winder having means for throwing yarn-masses out of 130

- operation, of traveling means for gaging thrown-out yarn-masses.
63. The combination, with a winder, of a traveling yarn-uniting means, and automatic means for suspending the travel of said yarn-uniting means. 70
64. The combination, with a winder, of a traveling yarn-uniting means, and means actuated by contact with a yarn-mass of predetermined size for suspending the travel of said yarn-uniting means. 75
65. The combination, with a winder, of a traveling yarn-uniting means, and feeler-actuated means for suspending the travel of said yarn-uniting means. 80
66. The combination, with a winder having means for throwing yarn-masses out of operation, of a traveling yarn-uniting means, and means traveling with said yarn-uniting means arranged to contact a thrown-out yarn-mass for suspending the travel of said yarn-uniting means. 85
67. The combination, with a winder, having means for throwing yarn masses out of operation, of a traveling yarn-uniting means; and means actuated by contact with a thrown-out yarn mass of predetermined size for suspending the travel of said yarn-uniting means. 90
68. The combination, with a winder having means for throwing yarn masses out of operation, of a traveling yarn-uniting means; a feeler traveling with said yarn-uniting means and arranged to contact thrown-out yarn masses; and means actuated by said feeler for suspending the travel of said yarn-uniting means. 100
69. The combination, with a winder, of a traveling yarn-uniting means; and means traveling with said yarn-uniting means for gaging yarn masses. 105
70. The combination, with a winder having means for throwing yarn masses out of operation, of a traveling yarn-uniting means; and means traveling with said yarn-uniting means for gaging thrown-out yarn masses. 110
71. The combination, with a winder, of a gage arranged to travel in a path parallel with the axis of the yarn masses, and arranged to contact with the peripheries of the yarn masses. 115
72. The combination, with a winder, of a yarn-uniting means arranged to travel in a path parallel with the axis of the yarn-masses; and a feeler traveling with said yarn-uniting means and arranged to contact the peripheries of yarn masses of predetermined size. 120
73. The combination, with a winder having means for throwing yarn masses out of operation, of yarn-uniting means arranged to travel in a path parallel with the axis of the thrown-out yarn masses; and a feeler traveling with said yarn-uniting means in position to contact with the peripheries of a yarn mass of predetermined size; and means actuated by said feeler for suspending the travel of said yarn-uniting means. 125
74. The combination, with a winder having means for throwing yarn masses out of operation, of a traveling yarn-uniting means; and means actuated by contact with a yarn mass in operative position for suspending the travel of said yarn-uniting means. 75
75. The combination, with a winder comprising a plurality of units, of a traveling yarn-uniting means adapted to operate upon units in inoperative condition; and means actuated by contact with a unit in operative condition for suspending the travel of said yarn-uniting means. 80
76. The combination, with a winder comprising a plurality of units, of a traveling yarn-uniting means adapted to operate upon units in inoperative condition; a feeler traveling with said yarn-uniting means arranged to contact a portion of the unit in operative condition; and means actuated by said feeler for suspending the travel of said yarn-uniting means. 85
77. The combination with a winder comprising a plurality of units, each unit comprising a yarn mass-supporting lever arranged to be swung to opposite sides of its pivot, of a traveling yarn-uniting means arranged to operate upon yarn masses at one side of the pivots of said levers; and a feeler carried by said yarn-uniting means in position to contact yarn masses at the opposite side of the pivots of said levers. 100
78. The combination, with a winder having means for transferring yarn-masses from one position to another, of a traveling yarn-uniting means adapted to act upon yarn masses in one position; a feeler carried with said yarn-uniting means in position to contact with yarn masses in the other position; and means actuated by said feeler for suspending the travel of said yarn-uniting means. 110
79. A winder having, in combination, means for winding a thread from a bobbin onto another sort of container; a knot-tying mechanism for operating upon said thread and a reserve thread to tie them together; and a pivoted arm arranged to engage said first-named thread and move it into operative relation to said knot tying mechanism. 115
80. A winder having, in combination, a mechanism for winding a plurality of threads; means for supporting active threads and reserve threads; and means for joining a reserve thread to an exhausted active thread. 120
81. The combination of two bobbin holders; yarn-mass supporting means; yarn-mass rotating means; a reserve thread-end 125

- holder; means for moving the yarn-mass supporting means out of operative position; a knot-tying mechanism adapted to receive the reserve thread end; mechanism 5 for finding an end on the yarn mass; mechanism for carrying the found end to the tying mechanism; and means for moving the yarn-mass supporting means into operative position.
- 10 82. The combination of a winder comprising a plurality of units arranged in a row, each unit comprising means for supporting a winding couple, and means for holding the end portion of a reserve thread; 15 and a thread-uniting mechanism arranged to travel along the row of units in the plane of said holding means, so as to be carried in its travel against the end portions of successive reserve threads, and means traveling 20 with said uniting mechanism for placing the end of an exhausted thread in operative relation to said uniting mechanism.
83. The combination of a winder comprising a plurality of units arranged in a row, each unit comprising means for supporting a winding couple, and means for holding the end portion of a reserve thread, 25 said holding means comprising a clamp and a bridge; and a thread-uniting mechanism arranged to travel along the row of units and through the spaces between the clamps and bridges of successive units, and means traveling with said uniting mechanism for placing an exhausted thread in operative 30 relation to said uniting mechanism.
84. The combination of a winder comprising a plurality of units arranged in a row, each unit comprising means for supporting a winding couple, and means for holding the end portion of a reserve thread; 35 and a thread-uniting mechanism arranged to travel along the row of units, the end portions of reserve threads being in the path of said uniting mechanism, said mechanism comprising a tying-bill and thread guides, and means traveling with said uniting mechanism for placing an exhausted thread in said thread guides and in operative relation to the tying-bill.
- 40 85. In a mechanism adapted to act upon a yarn-mass, the combination of means for picking up a thread on the periphery of the yarn-mass; and means for severing an adventitious strand connected to the picked-up 45 thread.
86. In a winder-tending mechanism adapted to act upon a yarn mass wound upon a container, a portion of the yarn being liable to lie upon the container beside the yarn mass; the combination of means 50 for picking up the thread; and means for severing it at a point between said picking-up means and the container.
87. In a winder-tending mechanism 55 adapted to act upon a yarn mass wound
- upon a container, a portion of the yarn being liable to lie upon the container beside the yarn mass; the combination of means for subjecting the periphery of the yarn mass to a suction air current; and means 70 for severing the portion of the yarn which extends to the container.
88. In a winder-tending mechanism, means for subjecting the periphery of a yarn mass to a suction air current to pick up the end of the thread; and means for revolving the yarn mass while subjected to the suction current.
89. In a winder-tending mechanism, two aligned yarn-mass-rotating rolls, the distance 80 between said rolls being less than the width of the yarn mass; and a suction device located between said rolls for picking up the free end of the yarn upon the periphery of said mass.
- 90 90. The combination of a rotary cam drum; a cheese-supporting lever arranged to swing to carry the cheese into and out of contact with the drum; means for moving said lever to place the cheese on the cam drum; and a hinged curved plate with which the cheese makes peripheral contact in moving toward the cam drum.
91. The combination of a rotary cam drum; a cheese-supporting lever which is 95 pivotally movable to carry the cheese into and out of contact with the drum; a carriage movable past said lever and cam drum; means on said carriage for moving the lever to place the cheese on the cam 100 drum; and a hinged curved plate on said carriage with which plate the cheese makes peripheral contact when moving toward the cam drum.
92. A winder having means for supporting a reserve thread; means for supporting a cheese, a carriage arranged to travel past said supporting means; a knotter mounted in said carriage in position to be carried against the reserve thread in the travel of 105 the carriage; means on said carriage for finding the end of the yarn on the cheese; means for carrying the found thread to a point adjacent the knotter; means for carrying said thread from said point into 110 the knotter; and means for actuating the knotter to unite the reserve thread and the found thread.
93. A winder having yarn-mass rotating means; a pivoted lever for supporting a 120 yarn-mass on said rotating means; a spring-pressed member arranged to bear against a portion of said lever; and means for moving aside said spring-pressed member to clear said lever portion.
94. The combination of means for winding yarn from bobbins onto containers; means for supporting reserve bobbins; means for stopping the rotation of the containers upon the exhaustion of the yarn; and 125 130

means for uniting the yarn on reserve bobbins to exhausted yarn, said uniting means being arranged to travel into operative relation with successive groups of containers and 5 bobbins.

95. The combination of a series of means for supporting winding couples, and automatic mechanism for repairing the yarn connections of the couples, said mechanism comprising a yarn-uniting means and means for moving said yarn-uniting means along said series.

96. A winder having a series of winder units; and a traveling winder-tending mechanism comprising a knot-tying mechanism and also comprising a pivoted arm for moving exhausted threads to the knot-tying mechanism.

97. The combination, with a winder having means for throwing yarn-masses out of operation, of means for gaging thrown-out yarn-masses.

98. The combination, with a winder, of automatically-actuated means for uniting a thread from a bobbin and a thread from another yarn-mass.

99.. A winder having, in combination, means for finding the loose thread end upon a thread container; a thread-uniting mechanism; and means for presenting said found end to said thread-uniting mechanism.

100. In combination, means for rotating a yarn mass, and means operating on the periphery of the mass for picking off the loose 35 thread end thereon.

101. A winder having, in combination, means for supporting a thread; a knot-tying mechanism; and means for moving said knot-tying mechanism in a circuit, a portion of which circuit is in proximity to said thread.

102. A winder having, in combination, means for supporting a thread; an endless track; a knot-tying mechanism; and means for moving 45 said knot-tying mechanism upon said track, a portion of which track is in proximity to said thread.

103. A winder having, in combination, a mechanism for winding a thread; a knot-tying mechanism; and means for moving said knot-tying mechanism in a circuit, a portion of which circuit extends transversely of the thread being wound.

104. A winder having, in combination, a mechanism for winding a thread, means for detecting the exhaustion of the thread being wound; means for holding a reserve thread; a knot-tying mechanism; and means for moving said knot-tying mechanism in a circuit, a portion of which circuit is in proximity to a portion of the thread being wound.

105. A winder having, in combination, a mechanism for winding a thread; means for detecting the exhaustion of the thread being

wound; means for holding a reserve thread; an air tube for receiving the end of the exhausted thread; a knot-tying mechanism; and means for moving said knot-tying mechanism in a circuit, a portion of which circuit is in proximity to a portion of the thread being wound.

106. A winder having, in combination, a mechanism for winding a thread; means for holding a reserve thread; a knot-tying mechanism; and means for moving said knot-tying mechanism in a circuit, a portion of which circuit is in proximity to a portion of the thread being wound and a portion of the reserve thread.

107. A winder having, in combination, a detector mechanism, a traveling knot-tying mechanism, and means moving with said knot-tying mechanism for restoring said detector mechanism.

108. A winder having an endless track, a thread-uniting mechanism mounted on said track; and means for moving said mechanism along said track.

109. A winder having an elongated framework, a straight row of pairs of bobbin-holders at opposite sides of the framework; a detector mechanism associated with each pair of bobbin-holders; and a thread-uniting mechanism arranged to travel around said framework and into proximity to the threads extending from bobbins in the bobbin-holders.

110. A winder having a rotary drum having a yarn-traversing groove in its periphery, means for supporting a yarn mass in contact with the periphery of the drum, means for removing the yarn mass from contact with the drum, and means for returning the yarn mass into contact with the drum.

111. A winder having a reserve thread holder, a knotter comprising a tying bill, means for causing relative movement between the knotter and the reserve thread holder to place a reserve thread in the tying bill, and means for moving an exhausted thread into the tying bill.

112. A winder having a rotary drum having a yarn-traversing groove in its periphery, a lever pivoted to swing in a vertical plane and arranged to support a yarn mass in contact with the periphery of the drum, means for swinging the lever to remove the yarn mass from contact with the drum, and means for swinging said lever to return the yarn mass into contact with the drum.

113. The combination with a winder comprising a yarn-mass-carrying lever, of an end-finder, and means for moving the lever to position the yarn mass with relation to the end-finder.

114. The combination with a winder comprising a yarn-mass-carrying lever, of an end-finding mechanism comprising a rota-

tory roll, a suction tube adjacent to said roll, and means for raising the lever and then permitting it to drop to place the yarn mass on said roll.

- 5 115. A winder having supports for a plurality of yarn winding containers; holders for an active and a reserve supply of thread for each winding container; a detector co-operating with each active thread; and automatic means controlled by said detector for stopping the winding of a yarn winding container when its active thread is exhausted; in combination with a winder tender co-operating in timed relation and in succession with each of the yarn winding containers and its active and reserve threads after its active thread has been exhausted, said winder tender having means to unite the reserve and active threads; and means to cause the winding operation to be resumed after the union is effected.
- 10 116. A winder having supports for a plurality of yarn winding containers; means for rotating said winding containers; holders for an active and a reserve supply bobbin for each winding container; a detector co-operating with each active thread; and automatic means controlled by said detector for stopping the winding of a yarn winding container when its active thread is exhausted; in combination with a winder tender co-operating in timed relation and in succession with each of the yarn winding containers and its active and reserve threads after its active thread has been exhausted, said winder tender having a knotter acting to tie the reserve and active threads together and to cut off their ends; and means to cause the winding operation to be resumed after the tying is completed.
- 15 117. A winder having supports for a plurality of yarn winding containers; and holders for an active and a reserve supply bobbin for each winding container, in combination with a winder tender co-operating in timed relation and in succession with each of the yarn winding containers and its active and reserve threads after its active thread has been exhausted, said winder tender having the following characteristics, namely, means for rotating a wound yarn mass in unwinding direction; means to remove the end of the thread from the yarn mass and to move said thread end into the neighborhood of the reserve thread; a knotter acting to tie the reserve and active threads together; a suction tube in the neighborhood of the knotter to carry away the cut off ends; and means to cause the winding operation to be resumed after the tying is completed.
- 20 118. A winder having a support for a yarn winding container; holders for an active and a reserve supply bobbin for the winding container; a clamp for the thread end of the reserve bobbin; a detector co-operating with the active thread; and automatic means controlled by the detector for
- 25 stopping the winding of the yarn winding container when its active thread is exhausted; in combination with a winder tender co-operating with the yarn winding container and its active and reserve threads after its active thread has been exhausted, said winder tender having the following characteristics, namely, means for rotating the wound yarn mass in unwinding direction; means to remove the end of the thread from the yarn mass and to move said thread end into the neighborhood of the clamped end of the reserve thread; a knotter acting to tie the reserve and active threads together and to cut off their ends, and means to cause the winding operation to be resumed after the tying is completed.
- 30 119. A winder having supports for a plurality of yarn winding containers, holders for an active and a reserve supply bobbin for each winding container; a clamp for the thread end of each reserve bobbin; a detector co-operating with each active thread; and automatic means controlled by said detector for stopping the winding of a yarn winding container when its active thread is exhausted; in combination with an automatic traveling winder-tender co-operating in timed relation and in succession with each of the yarn winding containers and its active and reserve threads after its active thread has been exhausted, said winder tender having the following characteristics, namely, means for rotating a wound yarn mass in unwinding direction; a suction tube acting to remove the end of the thread from the yarn mass and hold on thereto; means for moving the thread end extending from the wound yarn mass alongside the reserve thread; a knotter acting to tie the reserve and active threads together; a suction tube in the neighborhood of the knotter to carry away the cut off ends; and means to cause the winding operation to be resumed after the tying is completed.
- 35 120. A winder having, in combination, yarn-mass rotating means; a pivoted lever for supporting a yarn mass on said rotating means; a spring-pressed member arranged to act upon said lever; means to swing the lever to disengage the yarn mass from the rotating means; a carriage arranged to travel; means on the carriage to place said member in inoperative position; and means on said carriage to swing the lever in the opposite direction.
- 40 121. The combination of end-finding means including a suction tube, and means for successively presenting the peripheries of yarn masses to said end-finding means, the latter being adapted to hold the found ends.
- 45 122. A winder having end-finding means including a suction tube adapted to receive and hold the found end.

123. A winder having, in combination, means for rotating a yarn mass in a direction to unwind its thread, and means for picking up the loose thread end of said yarn mass.

124. A winder tender having, in combination, means for subjecting the periphery of a wound yarn mass to a suction air current to pick up the end of the wound thread; and means for revolving the yarn mass in a direction to unwind its thread while subjected to the suction current.

125. A winder having supports for a plurality of yarn winding containers; holders for an active and a reserve supply of thread for each winding container; a detector co-operating with each active thread; automatic means controlled by said detector for stopping the winding of a yarn winding container when its active thread is exhausted; in combination with a traveling winder tender co-operating in timed relation and in succession with each of the yarn winding containers and its active and reserve threads after its active thread has been exhausted, said winder tender having the following characteristics, namely, means for rotating a wound yarn mass in unwinding direction; means to remove the end of the thread from the yarn mass; means for moving the thread end extending from the wound yarn mass into the neighborhood of the reserve thread; a knotter acting to tie the reserve and active threads together; and means to cause the winding operation to be resumed after the tying is completed.

126. A winder having supports for a plurality of yarn winding containers; holders for an active and a reserve supply bobbin for each winding container; a clamp for the thread end of each reserve bobbin; a detector co-operating with each active thread; and automatic means controlled by the detector for stopping the winding of a yarn winding container when its active thread is exhausted; in combination with a traveling winder tender co-operating in timed relation and in succession with each of the yarn winding containers and its active and reserve threads after its active thread has been exhausted, said winder tender having the following characteristics, namely, means for rotating a wound yarn mass in unwinding direction; means to remove the end of the thread from the yarn mass; means for moving the thread end extending from the wound yarn mass into the neighborhood of the reserve thread; a knotter acting to tie the reserve and active threads together; and means to cause the winding operation to be resumed after the tying is completed.

127. A winder having a support for a yarn winding container; holders for an active and a reserve supply bobbin for the winding container; a clamp for the thread

end of the reserve bobbin; a detector co-operating with the active thread; an automatic means controlled by the detector for stopping the winding of the yarn winding container when its active thread is exhausted; in combination with a winder tender co-operating with the yarn winding container and its active and reserve threads after the active thread has been exhausted, said winder tender having the following characteristics, namely, means for rotating the wound yarn mass in unwinding direction; a suction tube acting to remove the end of the thread from the yarn mass and hold on thereto; means for moving the thread end extending from the wound yarn mass alongside the clamped end of the reserve thread; a knotter acting to tie the reserve and active threads together and to cut off their ends; a suction tube in the neighborhood of the knotter to carry away the cut off ends; and means to cause the winding operation to be resumed after the tying is completed.

128. A winder having supports for a plurality of yarn winding containers; a plurality of driving drums, one for each winding container; holders for an active and a reserve supply bobbin for each winding container; a clamp for the thread end of each reserve bobbin; a detector co-operating with each active thread; and automatic means controlled by said detector for stopping the winding of a yarn winding container when its active thread is exhausted; in combination with an automatic traveling winder tender co-operating in timed relation and in succession with each of the yarn winding containers and its active and reserve threads after its active thread has been exhausted, said winder tender having the following characteristics, namely, driving rolls for rotating a wound yarn mass in unwinding direction; a suction tube acting to remove the end of the thread from the yarn mass and hold on thereto; means for moving the thread end extending from the wound yarn mass alongside the clamped end of the reserve thread; a knotter acting to tie the reserve and active threads together and to cut off their ends; a suction tube in the neighborhood of the knotter to carry away the cut off ends; and means to cause the winding operation to be resumed after the tying is completed.

129. A winder having, in combination, means for revolving a yarn mass, thread-severing means, and pneumatic means for moving a thread from the yarn mass into operative relation to the severing means.

130. A winder having, in combination, means for revolving a yarn mass in the unwinding direction, and a shear located adjacent to the revolving means for severing a thread unwound from the yarn mass.

131. A winder having, in combination, an

end-finder, a knotter, means for placing a found thread in the knotter, and means for actuating the knotter to tie the found thread to a reserve thread.

5 132. A winder having a support for a yarn winding container, and holders for an active and a reserve supply of thread for said winding container; in combination with means to unite the reserve and active threads; a suction tube with an opening co-operating with the end of thread extending from the wound yarn on said container to hold the same; and means to engage said thread end between the yarn container and the suction opening and to transfer said thread into cooperative relation with said uniting means.

10 133. A winder having, in combination, a roll for rotating a yarn mass in unwinding direction, means for picking off a thread from the yarn mass during such rotation, a knotter, means for taking the picked-off thread to the knotter, means for stopping the rotation of the yarn mass, and means 15 for actuating the knotter to tie the thread to a reserve thread.

134. In a winder-tending mechanism, an end-finder; an arm for carrying a bight of yarn from the end-finder; a knot-tying mechanism; an arm for carrying a strand of yarn from the first mentioned arm into the knotter; and means adapted to coact with the second mentioned arm to clamp the thread.

135. In a winder, means for supporting a reserve thread; means for supporting a cheese; a carriage arranged to travel past said supporting means; a knotter mounted in said carriage in position to be carried 20 against the reserve thread in the travel of the carriage; means on said carriage for finding the end of the yarn on the cheese; means for carrying the found thread to a point adjacent to the knotter; an arm for carrying the found thread from said point into the knotter; a member carrying a clamping device with which said arm is arranged to coact to clamp the threads; and means for actuating the knotter to unite the 25 reserve thread and the found thread.

136. A winder having a winding roll and an unwinding roll, a thread-picking-up device near the unwinding roll, and a device for transferring a yarn mass from one roll to the other.

55 137. A winder having, in combination, an end-finder to find a thread-end upon a yarn mass, a knotter to tie such thread to a reserve thread, and thread-trimming means arranged to sever the first named thread before the knotter acts.

138. In a winder-tending mechanism, the combination of a suction tube for holding a thread-end, a knotter, a suction tube near the knotter, means for moving a bight of

the thread to a point near the knotter, means for moving a strand of the bight into the knotter, and means for severing said strand at a point between the suction tubes.

70 139. In a winder-tending mechanism, the combination of a suction tube for holding one end of a thread, a knotter, a suction tube near the knotter, means for moving the thread into the knotter, and means for severing said thread at a point between the suction tubes.

140. In a winder-tending mechanism, the combination of a suction tube for holding the end of a thread, a knotter, a pivoted arm adapted to swing against the thread and carry a bight of the thread to a point near the knotter, a hook into which one strand of the bight is carried during the movement of said arm, a suction tube near the knotter, means for moving said strand into the knotter and the second suction tube, and a shear blade co-operating with said hook to sever said strand.

80 141. A winder having, in combination, a suction tube for holding the end of an exhausted thread, a knotter for uniting a reserve thread and the exhausted thread and trimming off the waste ends, a shear for severing the exhausted thread between the suction tube and the knotter, said suction tube being adapted to carry off the waste portion severed by the shear, and a suction tube near the knotter to carry off the waste ends trimmed off by the knotter.

142. A winder having, in combination, means for supporting a winding couple, means for uniting the threads of the two members of the couple, and means for taking up slack in the united threads.

100 143. A winder having, in combination, means for winding a thread into a thread-mass; means for uniting another thread to the first mentioned thread, and additional means for revolving the thread-mass to take up slack in the united threads.

144. A winder having, in combination, a knotter for uniting two threads, means for winding up the united threads to take up slack therein, and other means for further winding up the united threads.

110 145. The combination of a cheese-winding unit and mechanism arranged to travel past said unit to unite the exhausted and a reserve thread to form a new strand, said mechanism comprising a reciprocating part and a member on said part adapted to engage the new strand, and means for moving said part to keep the portion of said strand which is between the cheese and said member in the vertical plane of the cheese.

120 146. The combination of a winder unit and mechanism arranged to travel past said unit to unite the exhausted and a reserve thread, said mechanism comprising a part

- mounted for reciprocation in the direction of travel of said mechanism, a member on said part adapted to engage the united threads, and means for reciprocating said 5 part.
147. The combination of a cheese-winding unit, a carriage arranged to travel past said unit, a part slidably mounted on said carriage, a member on said part adapted to 10 engage the thread of the unit, and means for moving said part to keep the portion of said thread which is between the cheese and said member in the vertical plane of the cheese.
148. In a winder-tending mechanism, the combination of means for tying a knot in a thread extending to a yarn mass, means for causing said tying means to travel in one direction with relation to the yarn 15 mass; a reciprocating member traveling with said tying means and adapted (upon its movement in the direction opposite to the traveling movement) to engage said thread at a point between the tying means 20 and the yarn mass; and an endless conveyer adapted to receive the threads from said member, said conveyer operating in a direction contrary to the direction of travel of said mechanism and being inclined toward 25 a portion of the unit so as to permit the thread gradually to approach said portion.
149. A winder having, in combination, means for supporting a winding couple, one member of the couple being movable into 30 and out of winding position; means for moving said member into winding position; and means to prevent reverse rotation of said member during movement into winding position.
150. A winder having, in combination, means for supporting a winding couple, one member of the couple being movable into and out of winding position; a knotter for tying the exhausted thread of said member 35 to the thread of another member; means for taking up slack in the tied thread; means for moving the first mentioned member into winding position; and means to prevent reverse rotation of said first named member 40 during the movement into winding position.
151. A winder having, in combination, a driving drum; a yarn-mass supporting lever arranged to swing to carry the yarn mass into and out of contact with the drum; 45 means for moving said lever to place the yarn mass on the drum; and means to prevent reverse rotation of the yarn mass during the movement of the yarn mass toward the drum.
152. A winder having, in combination, a driving drum; a yarn-mass-supporting lever arranged to swing to carry the yarn mass into and out of contact with the drum; means for moving said lever to place the 50 yarn mass on the drum; and a member with 55 which the yarn mass makes peripheral contact in moving toward the drum, to cause rotation of the yarn mass.
153. A winder having, in combination, a driving drum; a yarn-mass-supporting member which is movable to carry the yarn mass into and out of contact with the drum; a carriage movable past said member and drum; means on said carriage for moving the member to place the yarn mass on the 60 drum; and a yieldingly mounted member on said carriage with which the cheese makes peripheral contact when moving toward the drum.
154. A winder having, in combination, a plurality of units arranged side by side, each unit comprising a rotatory drum, a yarn mass support, a carriage arranged to travel along the row of units, a shelf on said carriage mounted to move in a path close to the 65 peripheries of the drums, and means to move said support to place the yarn mass on said shelf.
155. A winder having, in combination, a plurality of units arranged side by side, each unit comprising a rotatory drum, a yarn-mass-supporting lever pivoted to swing in a vertical plane, a carriage arranged to travel along the row of units, a shelf on said carriage arranged to move in a plane close 70 to the peripheries of the drums, means for swinging the lever to place the yarn mass on said shelf, and means engaging said lever to partially counterbalance the weight of the 75 yarn mass for a time after said shelf has moved out from under the yarn mass.
156. A winder having, in combination, means for rotating a yarn mass, a yarn mass support, devices for moving said support to move the yarn mass into and out of contact 80 with the rotating means, and means for cushioning the movement of the yarn mass into contact with the rotating means.
157. A winder having, in combination, means for rotating a yarn mass through peripheral contact with the latter, means to place the yarn mass in contact with the rotating means, and devices to insure gradual 85 acceleration of the yarn mass.
158. A winder having, in combination, a yarn-mass support, means for rotating the yarn mass through peripheral contact with the latter, means for moving the support to place the yarn mass in contact with the rotating means, means for partially counterbalancing the weight of the yarn mass for awhile after the yarn mass has been placed in contact with the rotating means, means for pressing the yarn mass against the rotating means, and means for disabling said 90 pressing means until after the counterbalancing means has ceased to act.
159. A winder having, in combination, a

yarn mass support; a rotatory drum arranged to rotate the yarn mass through peripheral contact with the latter; means for moving said support to place the yarn mass upon the

5 periphery of the drum; and means for laying upon the drum the thread extending to the yarn mass.

160. A winder having, in combination, a yarn mass support; a rotatory drum arranged 10 to rotate the yarn mass through peripheral contact with the latter; means for moving the support to place the yarn mass upon the periphery of the drum; a pivoted finger to receive the thread extending to the yarn 15 mass; and means for pivotally moving said finger to lay the thread on the periphery of the drum.

161. A winder comprising a row of 20 winder units; a winder-tending mechanism arranged to travel along said series; and means moving with the winder-tending mechanism for detecting whether one of the elements acted upon by each unit is in operative position.

25 162. A winder having, in combination, a plurality of winding units each including a detector element, means for causing said elements to move against the threads, and means to successively move the detector elements in the opposite direction.

163. A winder having, in combination, a movable support for a yarn mass being formed, a member attached to said support, means for pulling said member to move said 35 support, means normally held from action by the thread being wound for bringing said member and said pulling means into operative relation, and means for placing said thread-controlled means into position to receive the thread.

164. A winder having, in combination, a movable support for a yarn mass being formed, normally inoperative means for moving said support, a rock shaft having a 45 finger for rendering said moving means operative, a spring tending to rock said shaft, a finger fixed to said shaft and arranged to engage the thread being wound and thereby hold the shaft against rotation by the spring, and means for rocking the shaft against the tension of the spring to place the last mentioned finger in position to receive the thread to be wound.

165. A winder having, in combination, means for supporting a winding couple, one member of the couple being a bobbin, a knotter, and a device for carrying to the knotter the thread of the other member of said couple.

166. A winder having, in combination, a knotter comprising a tying bill, a reserve thread clamp and a reserve thread support arranged in planes at opposite sides of the tying bill, and means for causing relative

movement between the knotter on the one 65 hand and the clamp and support on the other hand to operatively associate the tying bill and the reserve thread.

167. A winder having a support for a yarn-winding container; and holders for an 70 active and a reserve supply of thread for the winding container; in combination with a winder tender coöperating with the yarn-winding container and its active and reserve threads, said winder tender having means 75 acting to unite the reserve and active threads and to cut off their ends.

168. A winder having a support for a 80 yarn-winding container; and holders for an active and a reserve supply of thread for the winding container; in combination with a winder tender coöperating in timed relation with the yarn-winding container and its active and reserve threads, said winder tender having a knotter acting to tie the 85 reserve and active threads together and to cut off their ends.

169. A winder having a support for a 90 yarn-winding container; and holders for an active and a reserve supply of thread for the winding container; in combination with a winder tender coöperating with the yarn winding container and its active and reserve threads, said winder tender having the following characteristics, namely, means for 95 moving the thread and extending from the wound yarn mass into the neighborhood of the reserve thread; and a knotter acting to tie the reserve and active threads together and to cut off their ends.

170. A winder having a support for a 100 yarn-winding container; holders for an active and a reserve supply of thread for said winding container; a detector coöperating with the active thread; and automatic means 105 controlled by said detector for stopping the winding when the active thread is exhausted; in combination with means to unite the reserve and active threads; and means to cause the winding to be resumed after the 110 union is effected.

171. A winder having a support for a 115 yarn-winding container; holders for an active and a reserve supply of thread for said winding container, a detector coöperating with the active thread; and automatic means controlled by said detector for stopping the winding of the yarn winding container when its active thread is exhausted; in combination with a winder tender co- 120 operating in timed relation with the yarn-winding container and its active and reserve threads after its active thread has been exhausted, said winder tender having means to unite the reserve and active threads; and 125 means to cause the winding operation to be resumed after the union is effected.

172. A winder having supports for a plu-

- rality of yarn-winding containers; holders for an active and a reserve supply of thread for each winding container; a detector co-operating with each active thread; and automatic means controlled by said detector for stopping the winding of a yarn-winding container when its active thread is exhausted; in combination with a winder tender coöperating with the yarn winding containers and their active and reserve threads after an active thread has been exhausted, said winder tender having means to unite the reserve and active threads; and means to cause the winding operation to be resumed after the union is effected.
173. A winder having a support for a yarn-winding container; holders for an active and a reserve supply bobbin for the winding container; and automatic means for stopping the winding of the yarn winding container when its active thread is exhausted; in combination with a winder tender coöperating with the yarn winding container and its active and reserve threads after its active thread has been exhausted, said winder tender having the following characteristics, namely, means for moving the thread end extending from the wound yarn mass into the neighborhood of the reserve thread; a knoter acting to tie the reserve and active threads together; and means to cause the winding operation to be resumed after the tying is completed.
174. A winder having, in combination, a plurality of winder units arranged in a row, each unit comprising two thread-supply holders, a yarn mass support, yarn mass rotating means, and a holder for a reserve thread end, in combination with a support extending along said row of units, and means coöperating automatically in succession with said units to unite the reserve thread of each unit to a thread extending from the corresponding wound yarn mass, said means being mounted on said support for movement along the row of units.
175. A winder having, in combination, a plurality of units, a support extending ad-

jacent to said units, and a winder tender traveling upon said support and coöperating automatically with said units to unite reserve threads to ends extending from the wound threads.

176. A winder having, in combination, supports for a plurality of active and reserve thread supplies, means for winding the active threads, and automatic mechanism for uniting a thread extending from a wound yarn mass to a reserve thread.

177. A winder having, in combination, supports for a plurality of active and reserve thread supplies, means for winding the active threads, and automatic mechanism for uniting an exhausted thread extending from a wound yarn mass to a reserve thread.

178. A winder having, in combination, supports for an active and a reserve thread supply, automatic means for winding the active thread to constitute a wound yarn mass, and automatic mechanism for uniting a thread extending from the wound yarn to the reserve thread and for cutting both threads.

179. A winder having a support for a yarn winding container; holders for an active and a reserve supply of the thread for each winding container; means to unite the reserve and active threads; a detector co-operating with the active thread and moving when the active thread is exhausted, and means controlled by said detector which render operable the uniting means upon the threads.

180. A winder having, in combination, means for winding a series of threads, a detector for each thread, and means arranged to travel along the series for successively resetting the detectors.

In testimony whereof I affix my signature in presence of two witnesses.

HOWARD D. COLMAN.

Witnesses:

JOHN F. ELWOOD,
LOUISE A. CULVER.

It is hereby certified that in Letters Patent No. 1,175,710, granted March 14, 1916, upon the application of Howard D. Colman, of Rockford, Illinois, for an improvement in "Textile-Machines," errors appear in the printed specification requiring correction as follows: Page 1, line 89, for the word "machine" read *mechanism*; page 2, line 24, for the abbreviation and numeral "Fig. 36" read *Fig. 26*; same page, line 67, before the word "mechanism" insert the compound word *winder-tending*; page 4, line 60, after the word "winder" insert the word *unit*; page 12, line 107, claim 13, after the word "traveling" insert the word *means*; page 22, line 82, claim 154, for the word "rotatary" read *rotatory*; and that the said Letters Patent should be read with these corrections therein that the same may conform to the record of the case in the Patent Office.

Signed and sealed this 18th day of April, A. D., 1916.

[SEAL.]

R. F. WHITEHEAD,
Acting Commissioner of Patents.

Cl. 242—44.
